CLAIM

The ornamental design for a flat lying foldable container with an integrated lid, as shown and described.

DESCRIPTION

FIG. 1 is a top, rear perspective view of a flat lying foldable container with an integrated lid according to the present invention, in its assembled configuration;

FIG. 2 is a bottom, front perspective view of the flat lying foldable container with an integrated lid of FIG. 1;

FIG. 3 is a front view of the flat lying foldable container with an integrated lid of FIG. 1;

FIG. 4 is a rear view of the flat lying foldable container with an integrated lid of FIG. 1;

FIG. 5 is a top view of the flat lying foldable container with an integrated lid of FIG. 1;

FIG. 6 is a bottom view of the flat lying foldable container with an integrated lid of FIG. 1;

FIG. 7 is a first side view of the flat lying foldable container with an integrated lid of FIG. 1;

FIG. 8 is a second, opposite side view of the flat lying foldable container with an integrated lid of FIG. 1;

FIG. 9 is a perspective view of the flat lying foldable container with an integrated lid of FIG. 1, with the lid open;

FIG. 10 is a top perspective view of the flat lying foldable container with an integrated lid of FIG. 1, in a collapsed configuration;

FIG. 11 is a bottom perspective view of the flat lying foldable container with an integrated lid of FIG. 1 (i.e., the container in FIG. 11 has been flipped over relative to FIG. 10);

FIG. 12 is a first end view of the flat lying foldable container with an integrated lid of FIG. 10;

FIG. 13 is an opposite end view of the flat lying foldable container with an integrated lid of FIG. 10;

FIG. 14 is a top view of the flat lying foldable container with an integrated lid of FIG. 10;

FIG. 15 is a bottom view of the flat lying foldable container with an integrated lid of FIG. 10;

FIG. 16 is a first side view of the flat lying foldable container with an integrated lid of FIG. 10;

(Continued)

FIG. 17 is a second, opposite side view of the flat lying foldable container with an integrated lid of FIG. 10; and, FIG. 18 is a side view similar to that of FIG. 17, but with the lid of the container folded under the flat lying container. Any broken lines shown are directed to environmental structure and are for illustrative purposes only. Any broken lines form no part of the claimed design.
